UNITED STATES PATENT OFFICE.

JOHN M. SMITH, OF RALEIGH, NORTH CAROLINA.

ADVERTISING DEVICE.

Application filed March 10, 1924. Serial No. 698,247.

To all whom it may concern:

Be it known that I, JOHN M. SMITH, a citizen of the United States, residing at Raleigh, in the county of Wake and State 5 of North Carolina, have invented new and useful Improvements in Advertising Devices, of which the following is a specification.

This invention relates to advertising devices and has for its object the provision of a novel wind or other power driven device including a plurality of swingable display plates or signs carrying any desired advertising matter, the device being equipped 15 with means for swinging the successive plates or signs into display position.

An important and more specific object is the provision of a device of this character including a stationary track on which the 20 swingable signs travel, the device further including a rotary shaft driven by a cup windmill and having a cam controlled arm for moving the successive plates.

A further object is the provision of a 25 device of this character which will make a very attractive and conspicuous display so that the advertising value will be correspondingly great while the entire effect is unique.

30 An additional object is the provision of a device of this character which will be comparatively simple and inexpensive in manufacture, positive in action, efficient and durable in service and a general improvement in the art.

With the above and other objects and advantages in view the invention consists in the details of construction to be hereinafter 40 more fully described and claimed and illustrated in the accompanying drawings, in which:

Figure 1 is a perspective view of the complete device,

45 Figure 2 is a horizontal section therethrough on the line 2—2 of Figure 1,

Figure 3 is a fragmentary side elevation,

Figure 4 is a detail view showing the cam action of the shifting arm,

50 Figure 5 is a detail section showing the governor,

Figure 6 is a detail view of a catch device.

Referring more particularly to the drawings the numeral 10 designates a hollow supporting base provided at its bottom with 55 a step bearing 11 for the lower end of a vertical operating shaft 12 which has its

upper end carrying a windmill or wind-wheel formed of radial arms 13 carrying funnel shaped cups 14.

Secured upon and rising from the base 60 10 in divergent relation are braces 15 which support a stationary track 16 which is semi-circular in shape. On the shaft are spaced collars 17 above which are located rings 18 which loosely encircle the shaft and 65 which are prevented from downward slipping by the collars 17.

I provide a plurality of sign plates 19 which bear any desired advertising matter and which are provided with screw eyes or 70 the like 20 pivotally and slidably engaged upon the rings 18. By this means it will be seen that the sign plates are freely swingable so as to be disposed at either side of the shaft 12 as clearly indicated. The lower 75 outer corners of the plates carry small brackets 21 within which are journaled rollers 22 traveling on the track 16 for guiding the plates during their swinging movement. At the upper corners of the 80 plates are laterally extending rods or wires 23 which carry co-acting buffers 24 which operate to hold the plates in properly spaced relation.

Secured upon and rising from the base 85 10 is a cam structure including upright legs 25 supporting a ring 26 which has one portion 27 elevated with respect to the remaining portion. Pivoted on the shaft at 28 is an arm 29 having its intermediate portion 90 curved to define a bearing member 30 which rides along the cam ring 26. When this arm is on the lower portion of the cam ring, the free end is out of the path of travel of the plates whereas when the bearing 30 is on the higher portion 27 of the ring the free 95 end of the arm is in position to engage a plate and move it from one side of the shaft to the other. It is of course obvious that the rise to the higher portion of the 100 ring must be located carefully with respect to the series of plates so that the arm 29 will be raised at the exact point to permit it to engage the end most plate.

For regulating the speed I provide a 105 drum 31 within the hollow base with which co-acts a pair of fly balls 32 on the free ends of leaf springs 33 secured to the shaft so that when the speed of the shaft 12 becomes excessive these fly balls will bear 110 frictionally against the drum 31 and retard the movement.

In the operation it is apparent that the wind-wheel causes the shaft 12 to rotate, carrying with it the arm 29. When the arm approaches the rise to the high portion 27 of the ring it is moved upwardly so that its free end will engage the end most one of the plates 19 and swing it through an arc of 180° so that it becomes the last of the series instead of the first. At this time the arm descends from the high portion 27 of the ring so that its end is retracted from engagement with the sign plate. As each plate is swung, it strikes against the previously swung plates and the momentum is sufficient to move the entire series slightly so that there will always be one plate ready to be engaged by the arm 29 upon upward movement thereof.

To prevent accidental swinging back of the sign plates during their movement, I provide a catch device at the receiving end of the track. The catch device is here represented as consisting of a pawl member 33 pivoted between ears 34 on the track 16 and having a depending stem 35 carrying a ball or other weight 36. The pivotal mounting is such that when the inclined surface of the pawl is engaged by the successive sign plates during their movement, the pawl will swing and permit the rollers on the signs to pass onto the track. If, however, there should be any tendency of the sign plates to move back off the track, the rollers 22 will engage the pawl 33 and be held against such undesired movement.

While I have shown and described the device as equipped with a windwheel for providing the motive power, it is obvious that use may be made of an electric motor, a spring motor or other equivalent drive mechanism. It is of course to be understood that I reserve the right to make such changes in the form, construction and arrangement of parts as will not depart from the spirit of the invention or the scope of the subjoined claims.

Having thus described my invention, I claim:

1. In a device of the character described, a base, a vertical shaft journaled therein, a cup windwheel on the upper end of the shaft, stop collars on the shaft, rings loosely encircling the shaft above the stop collars, a stationary track, a plurality of sign plates pivoted and slidable upon said rings and

carrying rollers traveling on the track, a cam mounted above the base, and a pivoted arm on the shaft traveling on said cam and movable thereby into upwardly extended position whereby to engage a sign plate 60 and swing it from one side of the shaft to the other.

2. In a device of the character described, a base, a vertical shaft journaled therein, a cup windwheel on the upper end of the shaft, stop collars on the shaft, rings loosely encircling the shaft above the stop collars, a stationary track, a plurality of sign plates pivoted and slidable upon said rings and carrying rollers traveling on the track, a cam mounted above the base, and a pivoted arm on the shaft traveling on said cam and movable thereby to upwardly extended position whereby to engage a sign plate and swing it from one side of the shaft to the other, and buffers located at the upper corners of the plates and engageable with one another whereby to space the plates apart and to communicate to the successive plate the impact of a moved plate whereby to move all the plates.

3. In a device of the character described, a base, a vertical shaft journaled therein, means for rotating the shaft, stop collars on the shaft, rings loosely encircling the shaft above the stop collars, a stationary track, a plurality of sign plates pivoted and slidable upon said rings, and carrying rollers traveling along the track, a cam mounted above the base, and a pivoted arm on the shaft traveling on said cam and movable thereby into upwardly extended position whereby to engage a sign plate and swing it from one side of the shaft to the other.

4. In a device of the character described, a vertical shaft journaled therein, a plurality of sign plates pivotally supported from the shaft, a stationary curved track pivoted above the base and serving to support the lower ends of the sign plates, a stationary cam member supported above the base in encircling relation to the shaft, and a vertically swingable arm pivoted upon the shaft and coacting with said cam, said cam acting to swing the arm upwardly into engagement between successive plates whereby to swing the plates from one side of the shaft to the other.

In testimony whereof I affix my signature.
JOHN M. SMITH.
